US0D1047270S

(12) **United States Design Patent** (10) **Patent No.:** **US D1,047,270 S**
(45) **Date of Patent:** **** Oct. 15, 2024**

(54) **VAPORIZER**

- (71) Applicant: **Airgraft Inc.**, Montreal (CA)
- (72) Inventors: **Mladen Barbaric**, Westmount (CA);
Kisae Kim, Westmount (CA);
Sungmoon Kim, Brossard (CA); **Bong Geun Kim**, Candiac (CA)
- (73) Assignee: **Airgraft Inc.** (CA)
- (**) Term: **15 Years**
- (21) Appl. No.: **29/743,388**
- (22) Filed: **Jul. 21, 2020**

Related U.S. Application Data

Primary Examiner — Rebecca Tsehay

(74) Attorney, Agent, or Firm — COOLEY LLP

CLAIM

The ornamental design for a vaporizer, as shown and described.

DESCRIPTION

FIG. 1 is a perspective view of an embodiment of the vaporizer;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The long-short-long broken lines immediately adjacent the shaded areas represent the bounds of the claimed design while the evenly spaced broken lines are directed to environment and are for illustrative purposes only; the broken lines form no part of the claimed design.
